UNITED STATES PATENT OFFICE.

GERTRUDE ANN LINDSAY, OF NEW YORK, N. Y.

GAME APPARATUS.

Application filed August 16, 1924. Serial No. 732,451.

To all whom it may concern:

Be it known that I, GERTRUDE ANN LINDSAY, a citizen of the United States, and a resident of the city of New York, borough of 5 Manhattan, county and State of New York, have invented a new and Improved Game Apparatus, of which the following is a full, clear, and exact description.

My invention relates to game apparatus 10 and it has for its object to provide interesting games which are played with representations of several types of hands cut into pieces which may be drawn from the center of the table and be fitted in relative 15 positions to produce types of hands which are normal or grotesque, according to the rules followed.

Additional objects of the invention will appear in the following specification in 20 which the preferred form of the invention is described.

In the drawings similar reference characters refer to similar parts in all the figures, in which—

25 Figures 1, 2, 3, 4, and 5 illustrate sets of pieces representing different types of hands;

30 Figure 6 is a view illustrating a card showing the type of person having one of the hands illustrated in the other figures; and

35 Figures 7 and 8 are views illustrating a modified form of the invention in connection with two additional types of hands.

40 By referring to the drawings it will be seen that seven types of hands are shown, but it will be understood that the particular types of hands which may be represented are immaterial, and that a larger or a smaller number of types may be employed.

45 In the drawings Figure 1 refers to the Mercury type of hand, Figure 2 to the Apollo type of hand, Figure 3 to the Saturn type of hand, Figure 4 to the Jupiter type of hand, Figure 5 to the Mars type of hand.

50 The representations of the different hands are cut into a number of pieces at the lines 10, so that each representation of a hand will have its Jupiter finger 11 cut into three pieces severed from the palm of the hand, and the Saturn finger 12, the Apollo finger 13, and the Mercury finger 14, will also each be cut into three pieces severed from the palm. The thumb 15 will be cut into 55 two pieces, and the palm of the hand 16 will be cut into four pieces at the lines 10.

Each player is given one of the well-known hand charts representing one of the hands which is indicated in the sets of pieces shown in Figures 1, 2, 3, 4 or 5 of the 60 drawings. The hand charts may be in the form shown in Figures 7 and 8 of the drawings. These hand charts, each of which corresponds with one of the sets of pieces referred to, may be duplicates of the sets 65 of pieces, the parts of which have not been severed. Each player is also given a picture of the person who is said to have the traits of character corresponding with the hand on the chart held by the player. 70

Five types of hands are shown in the drawings (Figures 1, 2, 3, 4 and 5), and these five hands may be used when there are five players, one player having a type 75 of a Mercury hand and pieces forming the Mercury hand such as is shown in picture 1, and also a picture of the type of Mercury person as shown in Figure 6. A second player will have a chart of the Apollo 80 type of hand and pieces forming an Apollo hand such as is shown in Figure 2, and also a picture of an Apollo type of person. A third player will have a chart of the Saturn 85 type of hand and pieces forming a Saturn hand such as is shown in Figure 3 and also a picture of a Saturn type of person. A fourth player will have a chart of the Jupiter type of hand and pieces forming a Jupiter hand such as is shown in Figure 4 and also a picture of a Jupiter type of person, 90 and the fifth player will have a chart of the Mars type of hand and pieces forming a Mars hand such as is shown in Figure 5 and also a picture of a Mars type of person. 95

Each player will then place all of his pieces in the center of the table and these pieces should be thoroughly mixed. Each player must then pick piece by piece from the pile of pieces in the center of the table to fit each section of the hand on his chart and build a hand on his chart which corresponds exactly with the chart. Should he pick up or draw a piece from the center of the table and find that it cannot be used on his chart he should restore it immediately to the center of the table and draw another piece. The one who builds and completes a perfect hand in the shortest time wins the game. 105

Another game may be played with the 110 apparatus after building each hand on its proper chart and the winner of the first

game may have the first play in the second game, choosing from the left a finger or other piece from the hand of the player on his left, placing it upon his own chart 5 after he has discarded the corresponding finger or piece. For instance, if he should choose an Apollo finger such as is shown at 13, he first discards an Apollo finger. The next player to the right chooses from 10 his left any finger or other part of the hand of the player at his left and places it likewise on his own chart and discards the corresponding finger. This leaves a 15 vacant space on the first player's chart which must be filled by the discarded finger or piece. When the fifth or last player is reached he is forced to take the discarded finger of the fourth player to complete his hand and he may exchange fingers or other 20 portions of the hand of any of the other players. When this has been done each player should endeavor to read aloud the hand which has been built up referring to any of the well-known booklets for the 25 information as to the different characteristics of the portion of the hand.

A third and very amusing game may be 30 played by permitting each player to build from the pile of pieces or sections on the middle of the table a grotesque hand without reference to the charts and when this has been done each player should endeavor to read the hand which he has built by referring to any of the well-known booklets 35 which furnish information with reference to the characteristics of different portions of the hand.

In Figures 7 and 8 cards are shown having 40 indicated thereon hands which may correspond with the hands shown in Figures 1, 2, 3, 4 and 5, or they may have indicated thereon other types of hands such as is shown in Figures 7 and 8; a Lunar hand being shown in Figure 7 and a Venus 45 hand being shown in Figure 8.

The cards shown in Figures 7 and 8 as well as additional cards having other types of hands indicated thereon are cut at 18

into squares 17, and these squares may be used instead of the pieces shown in Figures 50 1, 2, 3, 4 and 5 for playing the games which have been described.

Having thus described my invention, I claim as new and desire to secure by Letters Patent:

1. In a game apparatus, a plurality of representations of hands of different types, each with characteristics which distinguishes it from the representations of the other hands, the representations of the 60 hands being cut at similar places to form portions, the cut portions of one hand differing from the cut portions of the other hands.

2. In a game apparatus, a plurality of 65 hand charts of different types, each hand chart having features which distinguishes it from the other hand charts, a plurality of representations of hands of different types corresponding with the charts, the 70 representations of the hands being cut at similar places to form portions, the cut portion of one hand differing from the cut portions of the other hands.

3. In a game apparatus, a plurality of 75 hand charts of different types, each hand chart having characteristics which distinguishes it from the other hand charts, a plurality of representations of hands of different types corresponding with the hand 80 charts, the representations of the hands being cut into pieces.

4. In a game apparatus a plurality of 85 hand charts of different types of hands, a plurality of pictures of persons representing the different types and a plurality of representations of hands of different types corresponding with the charts, each representation of a hand being cut into pieces.

5. In a game apparatus, a plurality of 90 members having indicated thereon hands, the hands being of different types, each member being cut into pieces which correspond in size and shape with the pieces of the other members respectively.

GERTRUDE ANN LINDSAY.
